Horace L. Lamm

UNITED STATES PATENT OFFICE.

RUDOLF LOEB, OF JENKINTOWN, PENNSYLVANIA.

MECHANICAL MOVEMENT.

1,411,855.

Specification of Letters Patent.

Patented Apr. 4, 1922.

Application filed January 28, 1921. Serial No. 440,718.

To all whom it may concern:

Be it known that I, RUDOLF LOEB, a citizen of the United States, residing in Jenkintown, Montgomery County, Pennsylvania, have invented certain Improvements in a Mechanical Movement, of which the following is a specification.

My invention relates to certain improvements in mechanism for converting a rotary motion into a reciprocating motion, and one object of my invention is to provide means for imparting a limited forward motion to a device and to retard the return movement. A further object of my invention is to impart a quick forward motion to a reciprocating device and to return the device at a comparatively slow rate of speed. The invention can be used for a number of purposes, and one for which the invention is particularly adapted is the operation of a reciprocating cutting knife in which the forward cutting movement will be rapid, while the return movement will be retarded.

In the accompanying drawings:

Fig. 1 is a side view of a device illustrating my improved mechanical movement;

Fig. 2 is a sectional view on the line 2—2, Fig. 1;

Figs. 3, 4 and 5 are diagrammatic views;

Fig. 6 is a diagrammatic sectional view of a fabric cutting machine illustrating one application of my invention.

In the fabric cutting machine illustrated in Fig. 6, *a* is the fabric which is fed between two rolls *b* and *c*. In the roll *c* is a reciprocating knife *d* which cuts the fabric while the knife is passing over a limited portion of the surface of the roll *b*, from the point *x* to the point *x'*. The knife is returned to its original position while the roll *c* is completing its revolution.

By the use of my invention the knife *d* will be moved rapidly across the roll *c* and in contact with the lower roll *b*.

The return movement of the knife will be retarded and will take place while the roll *c* is completing one full revolution.

Referring now to Fig. 1, 1 is a bearing, 2 is a power shaft extending eccentrically through the bearing and secured to this power shaft is an arm 3 having a roll 4, projecting into a recess 5 of a sprocket wheel 6 in the present instance. The wheel is loosely mounted on the bearing 1, Fig. 2. Engaging with this sprocket wheel is a chain

7, which may be attached to the knife frame of the device shown in Fig. 6 or to any other mechanism which requires the peculiar movement described above.

Secured to the sprocket wheel 6 is an arm 8 to which is attached a spring 9, or a weight, if preferred. The purpose of this spring is to return the sprocket wheel to its first position when the wheel has been released from the control of the arm 3 on the driving shaft 2. It will be noticed that the wall 10 of the recess 5 is eccentric to the bearing and also to the shaft 2 and that it is in the form of a convolute, the two ends of the wall terminating in a shoulder 11.

Referring to Fig. 1, when the arm 3 is moved in the direction of its arrow the roll 4 is in contact with the shoulder 11 on the sprocket wheel and the wheel is moved in the direction of its arrow by the arm, owing to the wheel being eccentrically mounted in respect to the shaft 2. When the arm reaches a point indicated in Fig. 3 the shoulder is moved away from it, releasing the sprocket wheel, and as the spring 9 has been brought under tension due to the rotation of the wheel, the spring will tend to return the same to its first position, Fig. 1, but the roll is so proportioned to the eccentric wall 10 of the recess 5 that it will bear upon the wall with sufficient friction to retard the return movement due to the tension on the spring so that instead of the sprocket wheel rapidly returning, it will return slowly due to the frictional contact of the roll 4.

The eccentric surface of the wheel is so proportioned that the roll 4 will be in frictional contact with the surface until it reaches a point slightly in advance of the shoulder 11, and from this point to the shoulder the roll is clear of the surface and the spring 9 will complete the return of the knife to its first position and the shoulder will come in contact with the roll. As the chain 7 meshes with the teeth of the sprocket wheel it will be seen that any device attached to the chain will have a quick forward movement and a retarded return movement, whether the device be a cutting knife or other mechanism to which my mechanical movement can be applied.

While I have shown my invention as applied to a sprocket wheel, it will be understood that the shouldered cam element may be mounted independently of the sprocket wheel and connected thereto and in place

of the sprocket wheel a crank pin may be mounted on the element and connected to the device to be operated through a rod or other mechanism, and in some instances the cam element 6 may be secured to a shaft through which the motion may be imparted.

I claim:

1. The combination in an apparatus for converting a rotary motion into a reciprocating motion, of a reciprocable member and a rotating driving member including means for imparting a quick forward movement to said mechanism, a portion of said driving mechanism and the reciprocable member co-acting to retard the return movement of the latter.
2. The combination of an apparatus for converting a rotary motion into a reciprocating motion, said mechanism consisting of a rotating device having a projection; reciprocating means including a cam-device having a shoulder coacting with the projection on the rotating device, the latter as it completes its revolution bearing against the cam device and while the cam device is on its return movement.
3. The combination in a mechanical movement of a bearing; a shaft mounted eccentrically to the bearing; a driving arm on the shaft; a driven element mounted on the bearing and having a shouldered portion and a cam, said arm being arranged to contact with the shoulder to turn the element for a portion of its revolution; and means for returning the element when released from the control of the arm, the arm being positioned

to frictionally engage the cam to retard its return movement.

4. In a mechanical movement the combination of a bearing; a wheel loosely mounted thereon and formed with a cam terminating in a shoulder; a shaft eccentrically mounted in the bearing and having an arm; a roll on the arm positioned to coact with the shoulder and cam; and a spring for returning the wheel to its normal position, the arm being positioned to engage the shoulder for a portion of a revolution and thereafter disengage the same to permit the spring to return the wheel to its original position, the roll on the arm bearing upon the cam to retard its return movement.

5. The combination of a bearing; a sprocket wheel mounted thereon and having a cam terminating in a shoulder; a shaft eccentrically mounted in the bearing; an arm on the shaft; a roll on the arm positioned to frictionally engage the cam and arranged to bear against the shoulder; a spring attached to the sprocket wheel for returning the same to its normal position; and a chain engaging the sprocket wheel and attached to a device to be operated; the arm being mounted to engage the shoulder to turn the sprocket wheel a portion of a revolution then disengage said shoulder to allow the sprocket wheel to be returned by the spring, the roll being positioned to bear against the cam and retard the return movement of the sprocket wheel.

RUDOLF LOEB.
